UNITED STATES PATENT OFFICE.

OSCAR H. PIEPER, OF ROCHESTER, NEW YORK.

DENTAL APPARATUS.

Application filed March 21, 1923. Serial No. 626,574.

To all whom it may concern:

Be it known that I, OSCAR H. PIEPER, a citizen of the United States, residing at Rochester, in the county of Monroe and State of New York, have invented certain new and useful Improvements in Dental Apparatus; and I do hereby declare the following to be a full, clear, and exact description of the same, reference being had to the accompanying drawings, forming a part of this specification, and to the reference numerals marked thereon.

This invention relates to dental apparatus, and more particularly to equipment supporting means such as trays for holding hand implements, one object of the invention being to provide a simple, efficient, durable and convenient instrument tray of the general variety of that disclosed in Letters Patent No. 1,376,356, granted jointly to A. F. Pieper and myself April 26, 1921, for unitary dental apparatus. More specifically stated, the invention has the further object of providing a device of the above character in which a tray body is effectively supported and retained in position on a support in a conveniently detachable manner and is advantageously constructed not only for co-operation with the support but also for safety against injury when compactly assembled in quantity for shipment. To these and other ends the invention consists in certain improvements and combinations of parts, all as will be hereinafter more fully described, the novel features being pointed out in the claims at the end of the specification.

In the drawings:

Figure 1 is an elevation of a dental equipment apparatus or stand provided with an instrument tray embodying the present invention;

Figure 2 is an enlarged top plan view of the instrument tray, and

Figure 3 is a sectional elevation on the line 3^a—3^a of Figure 2.

Similar reference numerals throughout the several views indicate the same parts.

The invention is shown in the present instance, by way of illustration, as embodied in conjunction with an equipment supporting stand or column 5 adapted to be located at the side of a dental chair opposite the operator and carrying the various equipment desired, as fully shown and described in the said Letters Patent.

The column carries an arm 6 for supporting the usual dental engine 7 and has pivotally supported at an intermediate portion thereof a laterally extending arm 8, on the other end of which is pivoted an auxiliary supporting arm 9, which at its other end carries the instrument tray embodying the present invention.

The tray comprises a tray body proper 10 preferably in the form of a circular disk of glass or other vitreous material having at the periphery of its upper side a retaining flange 11, thus providing a convenient tray or table for supporting the various hand instruments or tools required in dentistry work. The under side 12 of the tray is formed with an abutment means preferably in the form of a projecting circular flange 13, for purposes which will more fully appear hereafter.

The supporting means for the tray body proper comprises, preferably, a sheet metal plate or disk 14 having an upwardly turned flange 15 at its periphery and within the latter a plurality of spaced cushioning elements, preferably in the form of hemispherical rubber studs 16 secured in place on plate 14 by rivet members 17 or in any other well known or suitable manner. These studs are located for engagement with the under side of the tray body 10 at its abutment means, for the purpose of supporting the tray and also positioning it when placed on the support and retaining it securely in such position in use. In the present instance the studs are located on a circle so as to engage the outer side of the tray flange 13 which fits snugly and securely within the circular studs, without coming in contact with the metal plate 14. The tray is thus not only securely retained in position but is cushioned by the rubber stud bodies to avoid the contact of glass on metal.

The tray support or plate 14 has secured at its center, as by means of screws or rivets 18, a hub 19 having a socket 20 in which is rotatably received the upper end of a short spindle (not shown) carried by the free end of the auxiliary arm 9. In this manner the tray and its support are rotatably and removably secured on the supporting arm so that they may be detached for cleaning or for replacement by other parts, as may be desired.

It is apparent from the above description and drawings that the tray body 10 is not

only effectively supported and retained on a cushioned seat, but may be conveniently rotated in use to bring the desired instruments into reach of the dentist and it may 5 also be conveniently removed and replaced on its supporting means. The projecting flange 13 not only serves to locate or center and retain the tray on its support as described above, but has the additional function of spacing the tray bodies when a plurality of the latter are placed one upon another or stacked in compact form for shipment, thereby preventing contact of the peripheral edges of adjoining trays which 10 would tend to chip and deface them.

The construction of the tray and its support is simple and convenient and durable in character, and therefore economical as to both manufacture and use.

20 5. I claim as my invention:

1. A dental apparatus comprising an instrument tray having a flange projecting from its under side, and a support provided with cushioning means disposed for engagement with the under side of said tray at 25 said flange to support said tray in position.

2. A dental apparatus comprising an instrument tray having a flange projecting from its under side, and a supporting plate provided with spaced studs of cushioning material disposed for engagement with the under side of said tray at 30 said flange to support said tray in position on said plate.

3. A dental apparatus comprising an in-

strument tray having abutment means on its under side and a support provided with spaced studs of cushioning material disposed for engagement with the under side of said tray at said abutment means to support said tray in position.

4. In dental apparatus, a circular instrument tray of vitreous material having a circular flange projecting from its under side, a circular supporting plate provided with a plurality of rubber studs for engagement with the under side of said tray at spaced points about said flange to support said tray in position, and means for supporting said plate.

5. In a dental apparatus, the combination of a supporting arm, a disk rotatably supported on said arm, an instrument tray having circular abutment means on its under side, and a plurality of elements of cushioning material disposed on said disk for supporting and positioning engagement with said tray adjacent said flange.

6. In a dental apparatus, the combination of an instrument tray having a circular flange projecting from its under side, a supporting disk provided with cushioning elements in spaced relation thereon for engagement with the under side of said tray adjacent said flange, a supporting arm, and means rotatably supporting said disk on said arm.

OSCAR H. PIEPER.
